CLAIM

The ornamental design for a breathing conduit, as shown and described.

DESCRIPTION

FIG. 1 is a front perspective view of a breathing conduit which embodies our design.

FIG. 2 is a rear perspective view thereof.

FIG. 3 is a top view thereof.

FIG. 4 is a bottom view thereof.

FIG. 5 is a left side view thereof.

FIG. 6 is a right side view thereof.

FIG. 7 is a rear view thereof; and,

FIG. 8 is a front view thereof.

The breathing conduit has been shown with break lines in its length.

The appearance of any portion of the article between the break lines forms no part of the claimed design.

The references to "left," "right," "front," "rear," "top," and "bottom" in the figure descriptions are not meant to require certain in-use orientation; the breathing conduit according to the claimed design may be used in any orientation.

The broken lines in the drawings illustrate portions of the breathing conduit which form no part of the claimed design.

1 Claim, 8 Drawing Sheets
